INDOOR TELEVISION ANTENNA

Philip Abraham Bernfeld, Flushing, N. Y.
Application June 18, 1956, Serial No. 41,940

Term of patent 3½ years

(Cl. D26—14)

Fig. 2.

3

Fig. 3.

3

Fig. 1.

Fig. 1 is a top plan view of an indoor television antenna, showing my new design;

Fig. 2 is a front elevational view of the same;

Fig. 3 is an end elevational view, looking in the direction of the arrows of line 3—3 on Fig. 1.

I claim:

The ornamental design for an indoor television antenna, as shown.
